UNITED STATES PATENT OFFICE.

CORNELIUS D. EHRET, OF PHILADELPHIA, PENNSYLVANIA.

APPARATUS FOR PRODUCING THERMIONIC EFFECTS.

Application filed April 29, 1919. Serial No. 293,485.

To all whom it may concern:

Be it known that I, CORNELIUS D. EHRET, a citizen of the United States, residing in the city and county of Philadelphia, State 5 of Pennsylvania, have invented a new and useful Apparatus for Producing Thermionic Effects, of which the following is a specification.

My invention relates to apparatus for producing thermionic effects, particularly in 10 circuits comprising a space, preferably within a vacuum, traversed by electrons for effecting current variation or control, for the purposes of amplification, rectification, production of oscillations, or other effects.

My invention resides in apparatus of the character referred to characterized by the 20 fact that upon a plate or anode circuit is impressed fluctuating or alternating current, with or without the presence of a source of current, as a battery, in the anode or plate circuit, with suitable control, as by a grid element whose potential depends upon the fluctuating electro-motive-force in the anode 25 or plate circuit or upon a fluctuating electro-motive-force superimposed upon another, as a substantially constant, electro-motive-force.

My invention resides also in apparatus for 30 producing oscillations of any suitable frequency by recourse to the apparatus above described.

My invention resides in novel features of 35 structure of the characters hereinafter described.

For an illustration of some of the various forms my apparatus may take, reference is to be had to the accompanying drawing, in which:

40 Figs. 1 and 2 are graphic representations of thermionic tube characteristics.

Fig. 3 is a diagrammatic view illustrating the superposition of fluctuating and substantially constant potential upon the plate 45 circuit of a thermionic structure.

Fig. 4 is a diagrammatic view illustrating the impression upon the plate or anode circuit of a thermionic device of a fluctuating potential which influences the potential of a 50 control member, as a grid.

Fig. 5 is a diagrammatic view of oscillation-producing means wherein a fluctuating potential is impressed upon the plate or anode circuit of a thermionic device, the grid 55 or control element being subjected both to the effects of the impressed electro-motive-

force and the effects of coupling of the grid circuit to the plate or anode circuit.

Fig. 6 is a diagrammatic view of oscillation-producing means wherein a fluctuating 60 potential is superimposed upon a substantially constant potential in the plate circuit of a thermionic device.

Fig. 7 is a graphic representation of superposition of fluctuating potential or current 65 upon substantially constant potential or current.

Fig. 8 is a diagrammatic view of a modified arrangement for producing oscillations.

Referring to Fig. 1, *c* is a curve whose 70 ordinates are plate currents of a three-electrode thermionic device and whose abscissæ are the potentials of the grid or control electrode. It will be understood that my invention is not limited to the characteristics of 75 this curve, the same being employed merely for illustrative purposes, it being understood that thermionic devices having different characteristic curves regarding grid potential and plate current are comprehended 80 within my invention. The curve indicates that as the grid potential rises or becomes more and more positive the plate current increases, assuming a given potential impressed upon the plate circuit. 85

In Fig. 2 the curve *d* is a characteristic of a thermionic device, ordinates representing the voltages impressed upon the anode or plate circuit and abscissæ are resulting plate or anode circuit currents. Here again it 90 will be understood that my invention is not limited to thermionic devices having this particular characteristic, but that any thermionic devices having different characteristics are contemplated within my invention. 95

A simultaneous inspection of Figs. 1 and 2 shows broadly that the plate current may be made to increase with rise of potential of the grid and also by increase in the voltage impressed upon the plate or anode circuit. 100

In accordance with my invention I simultaneously change the grid potential and the anode circuit voltage; and preferably in such directions as to cause cumulative 105 change in plate current.

It will be understood respecting the following description that the grid potential may be varied between any suitable points on a curve such as *c*, Fig. 1, either within a substantially straight portion thereof or within a curved portion, or both. And it will be 110

further understood that as to plate circuit voltage the same may be varied, simultaneously with grid potential variation, between any suitable points on a curve such as d , Fig. 5, either between points within a substantially straight portion thereof, or within a curved portion thereof, or both.

Referring now to Fig. 3, V is a thermionic device comprising a bulb evacuated to any 10 suitable degree, such as will permit only pure electron discharge or which will permit discharge due to presence of gas or gases of any suitable nature and quantity. Within the bulb are disposed the plate or anode p , 15 and electron-emitting body f , as an incandescent filament, with a control electrode or grid g between them. The temperature of the filament f is determined as usual by the amount of current passed therethrough from 20 a suitable source, as battery b . In the plate or anode circuit are connected the winding T , source B of substantially constant potential, as a battery of suitable voltage, and the secondary of a transformer T^1 in whose primary circuit is connected the source S of 25 fluctuating or alternating current, this being a generic representation of any such source, including a dynamo-electric generator, an alternating or direct current controlled or 30 varied by a microphone, received radio telegraphic or telephonic energy, received telegraphic or telephonic energy from a line wire system, etc. T may be any translating device, as a telephone receiver in which are 35 to be reproduced signals or messages represented by fluctuating or alternating current from any source in the primary of the transformer T^1 . Or T may be the primary winding of a transformer whose secondary 40 delivers energy to any suitable or desirable device, as a telephone receiver or further thermionic devices of the same character or any 45 other suitable character.

The grid g is connected to any suitable 50 point in the secondary of the transformer T^1 or to any suitable point with respect to the source B , or, generally, to any suitable point 55 in the external circuit between the filament f and plate p . At s in the grid circuit is shown a battery or condenser. When s is a battery it may serve to give to the grid g any suitable normal potential, for example, a negative potential. The battery or condenser s may be, however, omitted, if desirable.

With the filament f at suitable temperature there will be a predetermined normal anode or plate circuit current due to the source B . Upon the plate circuit potential 60 or voltage is then impressed a fluctuating or alternating potential by the transformer T^1 , the one potential being superposed upon the other and producing an effect which graphically may be represented as in Fig. 7. The 65 potential of the grid g will rise and fall also

in suitable or predetermined relation with respect to the rise and fall of potential impressed upon the anode or plate circuit, a rise in potential, as indicated by Fig. 1, causing an increase of plate current for a 70 given plate circuit potential, while a simultaneous rise of voltage in the plate circuit due to the transformer T^1 will cause, as indicated by Fig. 2, a further increase in plate circuit current. Accordingly a great plate current change is effected due both to change of grid potential and change of electro-motive-force impressed upon the anode circuit; and, further, the grid potential is related to or dependent upon the anode or plate circuit potential.

The source S therefore not only varies the potential of the grid and the potential impressed upon the anode circuit, thereby producing a greater fluctuation in T , but energy of fluctuating or alternating current 85 may be transferred by the source S into the anode or plate circuit, such energy being combined with the energy from source B .

In Fig. 4 the arrangement is similar to 90 that in Fig. 3, except that the plate circuit battery or source B is omitted. In this case the energy for the anode or plate circuit is supplied by the source S , the potential of the grid g , however, being determined by 95 the potential impressed upon the anode or plate circuit. The source of current or condenser s may be employed or not, as may be found suitable or desirable. The potential of the grid g is therefore dependent 100 upon the potential impressed upon the anode circuit, and the grid circuit connection is to a point intermediate the filament and plate in the external anode circuit. There is in this case no superposition, such as in Fig. 105 3, of alternating or fluctuating potential or current upon normally existing plate circuit potential or current.

In Fig. 5 there is in the plate circuit of an oscillator the primary of an output transformer T^2 shunted by a variable condenser C , in series with the secondary of the transformer T^1 . The grid g is connected through a secondary t , in inductive relation with the primary of the transformer T^2 , to any suitable point on the secondary of the transformer T^1 . Accordingly the grid is coupled to the plate circuit, which in turn is connected to a point whose potential will be intermediate that of the filament and the plate, the actual potential of the grid g being dependent upon the potential of such point, the potential produced by the coupling coil t and the potential of the battery s , if employed. Accordingly oscillations 115 will be produced in the plate circuit whose energy is delivered to the secondary of the transformer T^2 for any suitable purposes, as for radio telegraphy or telephony, or for 120 impression upon a line wire circuit, delivery 130

- to amplifying means or for any other purpose, the source S being generically any source of fluctuating or alternating current hereinbefore referred to.
5. In Fig. 6 is shown an oscillation-producing arrangement, in general similar to that shown in Fig. 5, except that in the plate circuit there is, as in Fig. 3, a source of current or potential B .
10. In Fig. 8 the grid circuit of an oscillator is coupled by t to the plate circuit, there being provided, if desired, an adjustable tuning condenser C^1 , in the grid circuit. In parallel to the variable condenser C and primary of transformer T^2 , in the plate circuit, are connected the choke coil L , battery B , and secondary of transformer T^1 .
15. In the oscillator of Fig. 5 all or substantially all of the energy to be converted into oscillations is derived from the source S . In Figs. 6 and 8, employing batteries B , the energy of the oscillations may be derived from the battery B and additional energy delivered by the source S ; or the energy for the oscillations may be principally or entirely supplied by the battery B and the source S with transformer T^1 employed simply for varying the amplitude of the oscillations.
20. In all of the oscillators above described the grid potential varies with variation of potential of the plate circuit, and in consequence the amplitude of the oscillations is the greater.
25. What I claim is:
1. The combination with a thermionic device comprising an anode, cathode and control electrode, of an anode circuit, a source of fluctuating current independent of said device impressing fluctuating current upon said anode circuit, and an aperiodic connection to said control electrode from a point between the terminals of said source.
  2. The combination with a thermionic device comprising an anode, cathode and control electrode, of an anode circuit, a source of fluctuating current in said anode circuit, an aperiodic connection to said control electrode from a point between the terminals of said source, and a source of uni-directional potential in said connection.
  3. The combination with a thermionic device comprising an anode, cathode and control electrode, of an anode circuit, a source of fluctuating current of audio frequency representing sound waves, a transformer whose primary includes said source and whose secondary is connected in series in said anode circuit, and a connection to said control electrode from a point between the terminals of said transformer secondary.
  4. The combination with a thermionic device comprising an anode, cathode and control electrode, of an anode circuit, a source of fluctuating current, a transformer whose
- primary includes said source and whose secondary is connected in series in said anode circuit, an aperiodic connection to said control electrode from a point between the terminals of said transformer secondary, and a source of uni-directional potential in said connection.
5. The combination with a thermionic device comprising an anode, cathode and control electrode, of an anode circuit, a control electrode circuit coupled thereto for producing oscillations, a source of fluctuating current independent of said device impressing upon said anode circuit fluctuating current transformed into oscillations by said coupled circuits, and a connection to said control electrode from a point between the terminals of said source.
6. The combination with a thermionic device comprising an anode, cathode and control electrode, of an anode circuit, a control electrode circuit coupled thereto for producing oscillations, a source of fluctuating current in said anode circuit, an aperiodic connection to said control electrode from a point between the terminals of said source, and a source of uni-directional potential in said connection.
7. The combination with a thermionic device comprising an anode, cathode and control electrode, of an anode circuit, a control electrode circuit coupled to said anode circuit for producing oscillations, a source of fluctuating current transformed into oscillations by said coupled circuits, a transformer having said source in its primary circuit and having its secondary connected in said anode circuit, and a connection to said control electrode from a point between the terminals of said secondary.
8. The combination with a thermionic device comprising an anode, cathode and control electrode, of an anode circuit, a control electrode circuit coupled to said anode circuit for producing oscillations, a source of fluctuating current, a transformer having said source in its primary circuit and having its secondary connected in said anode circuit, an aperiodic connection to said control electrode from a point between the terminals of said secondary, and a source of uni-directional potential in said connection.
9. The combination with a thermionic device comprising an anode, cathode and control electrode, of an anode circuit normally without substantial energy, a source of fluctuating current independent of said device in said anode circuit and constituting substantially the sole source of current for said anode circuit, and a connection to said control electrode from a point between the terminals of said source.
10. The combination with a thermionic device comprising an anode, cathode and control electrode, of an anode circuit nor-

normally without substantial energy, means delivering fluctuating current to said anode circuit and constituting substantially the sole source of current for said anode circuit, a connection to said control electrode from a point between the terminals of said means, and a source of uni-directional potential in said connection.

11. The combination with a thermionic device comprising an anode, cathode and control electrode, of anode and control electrode circuits coupled to each other for producing oscillations, a source of fluctuating current independent of said device and constituting substantially the sole source of current for the production of oscillations, and a connection to said control electrode from a point between the terminals of said source.

12. The combination with a thermionic device comprising an anode, cathode and control electrode, of anode and control electrode circuits coupled to each other for producing oscillations, means delivering fluctuating current and constituting substantially the sole source of current for the production of oscillations, a connection to said control electrode from a point between the terminals of said means, and means for impressing upon said control electrode a negative potential.

13. The combination with a thermionic device comprising an anode, cathode and control electrode, of an anode circuit, a source of fluctuating current of audio frequency independent of said device in said anode circuit, and a connection to said control electrode from a point between the terminals of said source.

14. The combination with a thermionic device comprising an anode, cathode and control electrode, of an anode circuit normally without substantial energy, a source of fluctuating current of audio frequency independent of said device and representing sound waves and constituting substantially the sole source of current for said anode circuit, and a connection to said control electrode from a point between the terminals of said source.

15. The combination with a thermionic device comprising an anode, cathode and control electrode, of an anode circuit nor-

mally without substantial energy, means delivering fluctuating current of audio frequency representing sound waves to said anode circuit and constituting substantially the sole source of current for said anode circuit, a connection to said control electrode from a point between the terminals of said means, and a source of uni-directional potential in said connection.

16. The combination with a thermionic device comprising an anode, cathode and control electrode, of anode and control electrode circuits coupled to each other for producing oscillations, a source of fluctuating current of audio frequency independent of said device and representing sound waves and constituting substantially the sole source of current for the production of oscillations, and a connection to said control electrode from a point between the terminals of said source.

17. The combination with a thermionic device comprising an anode, cathode and control electrode, of anode and control electrode circuits coupled to each other for producing oscillations, means delivering fluctuating current of audio frequency representing sound waves to said anode circuit and constituting substantially the sole source of current for the production of oscillations, a connection to said control electrode from a point between the terminals of said means, and a source of uni-directional potential in said connection.

18. The combination with a thermionic device comprising an anode, cathode and control electrode, of connections forming anode and control electrode circuits, means effecting a feed-back between said anode circuit and said control electrode, an independent source of fluctuating current of constant frequency independent of said feed-back, said source connected in said anode circuit, and means for subjecting said control electrode to a potential varying at the frequency of said source comprising a connection to said control electrode from a point intermediate the terminals of said source.

In testimony whereof I have hereunto affixed my signature this 28th day of April, 1919.

CORNELIUS D. EHRET.
